Primary Examiner — Jack Reickel*Assistant Examiner* — Bobby W Jones, II(74) *Attorney, Agent, or Firm* — BakerHostetler(57) **CLAIM**

The ornamental design for a filter cartridge as shown and described.

DESCRIPTION

1. Filter cartridge

1.1 : Perspective

1.2 : Front

1.3 : Top

1.4 : Right

The broken lines in the drawings illustrate portions of the filter cartridge which form no part of the claimed design; the back view is omitted because it is the same as the front view; the bottom view is omitted because it is the same as the top view; and the left view is omitted because it is the same as the right view.
